MACHINE FOR MARKING CIRCULAR KNIT
HOSIERY FOR BOARDING

Robert J. Moody and John E. Taylor, Franklin,
N. H., assignors to Scott & Williams, Incorporated,
Laconia, N. H., a corporation of Massachusetts

Application April 16, 1946, Serial No. 662,536

1 Claim. (Cl. 66—1)

This invention relates to a knitting machine having means for marking hosiery knit of a thread formed, for example, of a material such as the synthetic fibre forming polymeric amides known as "nylon" which is adapted to be set to a definite shape by subjecting the material to heat or heat and moisture as in the hosiery preboarding operation. In order that the hosiery may be properly shaped by the preboarding operation it is necessary that the hosiery be placed on the preboarding form with particular wales at the back and front of the hosiery exactly following the back and front edges, respectively, of the thin flat form used in this operation. In boarding full-fashioned hosiery, the seam at the back and bottom of the hosiery provides a raised guide enabling the operator to rapidly and accurately position the hosiery on the boarding form by placing the hosiery seam along the back edge of the form, an operation which can be carried out by feeling the position of the seam on the form. With seamless hosiery there is no seam to guide the operator and in order to place seamless hosiery on a boarding form so as to have the hosiery present the most attractive appearance when offered for sale, it is necessary to place particular wales of the hosiery on the back and front edges of the form. Careful inspection and adjustment, therefore, are required to insure seamless hosiery being properly placed on the form and the operation is slow and costly. It is an object of this invention to provide a knitting machine having improved means for marking hosiery during the knitting thereof so as to properly and quickly guide the placing of the hosiery on a form.

The invention is shown in the drawings in connection with a Scott and Williams circular knitting machine for knitting hosiery having turned welts, the machine being of the general construction shown in the patent to Scott, No. 1,282,958, issued October 29, 1918, and provided with patterning mechanism comprising jacks and jack selecting means such as are shown in the patent to Page, No. 1,969,853 issued August 14, 1934, and only such parts of the knitting machine are shown as are necessary to clearly illustrate the invention.

In the drawings:

Fig. 1 is a partial view in side elevation of a knitting machine having a marking means in accordance with this invention, parts being broken away to show other parts more clearly;

Fig. 2 is a partial view in side elevation showing the side opposite to that of Fig. 1 some parts

being omitted to show the remaining parts more clearly;

Fig. 3 is a partial top plan view of the machine shown in Fig. 1, parts being broken away to show other parts more clearly;

Fig. 4 is a fragmentary view in elevation looking from the left in Fig. 1;

Fig. 5 is a partial vertical sectional view taken at a needle selected for marking the fabric and showing the relations of the needle and intermediate and pattern jacks to each other and to certain operating cams;

Fig. 6 is a fragmentary view in elevation showing the relation of the pattern jacks and the jack selecting lever provided in connection with this invention;

Fig. 7 is a perspective view showing needle selecting levers detached from the machine;

Fig. 8 is a fragmentary plan view showing the cam operating the jacks of selected needles to which coloring matter is to be applied;

Figs. 9 and 10 are views in elevation of the back and front, respectively, of hosiery having coloring material applied by a machine in accordance with this invention; and

Fig. 11 is an enlarged view of a fragment of the hosiery fabric showing coloring material applied to the loops of two adjacent wales.

As shown in Figs. 9 and 10, hosiery marked by a machine in accordance with this invention has a guide mark M of a width of one or more needle wales which may extend down selected wale or wales of the back of the leg L from the start of the turned welt W to the heel H. The mark is omitted from the heel and toe but extends along the bottom of the sole S. A similar guide mark M' may extend along selected wale or wales of the front of the leg from the start of the welt W to and along the top of the instep I to the toe. The guide marks M and M', preferably, are off-set several wales from the exact back and front wales of the stocking so as to appear on the same side of the form in the preboarding operation, both marks being continuously visible to the operator and thus permitting adjustment of the stocking on the form to be readily made. Preferably the guide mark is formed of a fugitive dye contrasting sufficiently in color with the thread of which the hosiery is knit to be readily seen when the hosiery is being placed on the preboarding form. As the preboarding operation sets the thread of which the hosiery is knit so that the hosiery tends to maintain the shape and size given it by the preboarding operation, the removal of the fugitive dye forming the guide mark during the subse-

quent dyeing and finishing operations does not interfere with rapid and efficient boarding of the hosiery as the shape assumed by the hosiery guides its placing on the boarding form.

The machine for forming the guide mark or marks on the hosiery during the knitting thereof shown in the drawings is a circular hosiery knitting machine having a needle cylinder 260 mounted for rotation in a suitable frame and having needles N, intermediate jacks 732 and 10 pattern jacks 736 alined in the grooves thereof, there being a jack of each kind for each needle. The machine is also provided with the usual operating cams and yarn fingers operated by push rods from cams on the main pattern drum 120. The pattern jack selecting means provided comprises a pattern drum 800 rotated step by step in the usual way and operating reader cams 820 to select jacks for operating needles in the usual manner.

A guide mark is formed in the hosiery by applying a fugitive dye to the upper ends one or more needles knitting the central wale or wales at the back or back and front of the hosiery, or knitting selected wales adjacent the back and front of the stocking. In order that the dye may be applied to the desired needle or needles only, such needles are selected by being differentiated in position during each revolution of the needle cylinder when the guide mark is being formed prior to the operation of the adjacent needles to take the thread for knitting. To secure the differentiation in position of the selected needles N', the jacks 736b for these needles have an upper portion of their operating butts 736c cut away so that when rocked by the usual cam 100 during each revolution all patterning jacks 736 except the jacks 736b for the selected needles will have their operating butts 736e engaged by a lever 60 pivotally mounted below the usual "make-up" lever 61 on the pin mounted in the lower bed plate B on which the reader cams 820 for the patterning jacks are mounted. To operate the lever 60 there is attached to an end of the main pattern drum 120 a pattern disk 120a which rotates with the main pattern drum 120 and is provided with cams 501, 501a and 501b adapted to engage a pin 64 mounted in an arm 66 which is pivotally mounted on the machine frame. The pin 64 projects on both sides of the arm 66 and has secured thereon, on the other side of the arm 66 from the cam 501, the looped end of a Bowden wire 68, the opposite end of which is connected to an end of the lever 60. A spring 70 connected between the arm 66 and the machine frame opposes operation of the arm 66 by the cams 501, 501a and 501b to permit lever 60 to be moved to its jack engaging position by a spring 72 connected between the lever 60 and the machine frame end, when the cam has released the lever 60, serves to return the lever 60 to its inoperative position. The lever 60, when in jack engaging position, engages the jack operating butts 736e of all jacks except the selected jacks 736b and forces back the lower portions of the engaged jacks so that their operating butts pass the usual jack operating cam 113 and are not operated thereby. The jacks 736b for the selected needles, not having had their operating butts pressed inwardly, have their operating butts 736c engaged by the jack operating cam 113 and the jacks and selected needles N' are raised thereby prior to the raising of adjacent needles to take the yarn for knitting.

In the machine shown the latch ring 550 and the bracket 1 attached to the latch ring and supporting the dial operating means can be raised being pivotally connected as at 552 to a standard mounted on the upper bed plate A. To apply the coloring material to the differentiated needle or needles there is provided a container 2 for liquid coloring material having a detachable top or cover 2a to which is attached a light metal tube 4 having a wick 6 therein, the wick projecting from the tube at both ends so as to have one end immersed in the liquid coloring material and the other end exposed for contact with the hooks of the differentiated needles. 15 The metal tube 4 is secured by a clip 8 to a plate portion 9 of a bracket 10. The bracket 10 is formed with spaced lugs 11 which are pivotally connected to a base plate 12 secured by a screw 13 to the bracket 1 and with a lug 14 to which 20 is connected one end of a Bowden wire 16, the opposite end of which is connected to a pin 17 on the lever 66. A stop member 18 threaded into an opening in an extension 12a of the base plate 12 and secured in position by a set screw 25 19 serves to limit pivotal movement in the direction of the needles of the plate portion 9 and the tube 4 secured thereto while a spring 20 secured to the clip 8 by the clip retaining screw 21 and to the gear casing 22 cooperates with 30 the weight of the container 2 in biasing the plate portion 9 for movement in the direction bringing the wick 6 in the tube 4 into contact with the differentiated selected needle or needles N'. The manner of securing the tube 4 and the ease of varying the shape of the tube permits of readily adapting the apparatus to suit different conditions but in general the apparatus is so mounted that the wick end which engages the selected needle or needles is slightly below 35 the level of the liquid color in the container. Adjusting the position of the wick end with respect to the level of the liquid color provides a limited control of the rate of flow of the liquid color to the needles.

45 In the operation of the knitting machine disclosed, the make-up lever 61 is operated to select the needles to take the thread for the starting course in the usual manner and, where the guide mark is placed in the welt, a cam, as the cam 501a, will operate the arm 66 to permit the spring 72 to place the selecting lever 60 in operative position and the spring 20 to place the wick 6 in position to be engaged by a differentiated selected needle or needles upon completion of the 50 make-up or starting courses. The cam 501a is a two-step cam, the first step being designed to render the selector lever 60 operative to select the jacks of the needles N' to be raised and the wick 6 not being brought to a position in which it engages the selected needles N' until the pin 64 in arm 66 rests on the second step of the cam. The pattern drum 120 is operated to shift the cam 501a from the pin 64 as the knitting of the welt fabric is completed permitting the spring 60 65 70 to operate the lever 66 to return the lever 60 and the wick 6 to their inoperative positions for the transfer of the loops of the starting course to the welt. If following the regular welt, a shadow welt having patterning for identification is knit, the lever 60 and wick 6 are retained in inoperative position and are not returned to operative position until the knitting of the leg is begun. The lever 60 and the wick 6 are maintained in operative position throughout the knitting 75 of the leg, as by the cam 501, and are with-

drawn from operative position at the beginning of the knitting of the heel. Upon completion of the heel, a cam, as cam 501b, returns the lever 60 and wick 6 to operative position and maintains them in operative position throughout the knitting of the instep and sole and is operated to permit their return to inoperative position at the beginning of the knitting of the toe.

What is claimed is:

In a marking device for circular knitting machines having means for differentiating selected needles, a container for a fluid color, a wick having one end in said container and the other end arranged for engagement by a differentiated selected needle, tubing attached to said container and enclosing said wick, supporting means en-

gaging said tubing, means pivotally mounting said supporting means and means for operating said supporting means to shift said wick to and from its position for engaging said selected needle.
